AERATOR FOR A SEWAGE SYSTEM

David S. MacLaren, 21176 Brantley Road,
Shaker Heights, Ohio 44120

Continuation of abandoned design application Ser. No.
276,078, July 28, 1972. This application Apr. 17, 1974,
Ser. No. 461,493

Term of patent 14 years

Int. Cl. D15—99; D23—01
U.S. Cl. D55—1 D

FIG. 3

FIG. 2

FIG. 1

FIG. 6

FIG. 5

FIG. 4

FIG. 9

FIG. 8

FIG. 7

FIG. 12

FIG. 11

FIG. 10

FIG. 15

FIG. 14

FIG. 13

FIG. 18

FIG. 17

FIG. 16

FIG. 1 is an elevational view of an aerator for a sewage system embodying my new design;

FIG. 2 is a top plan view thereof;

FIG. 3 is a bottom plan view thereof;

FIG. 4 is an elevational view taken 90 degrees from FIG. 1;

FIG. 5 is an elevational view taken 90 degrees from FIG. 4;

FIG. 6 is an elevational view taken 90 degrees from FIG. 5;

FIG. 7 is an elevational view of a modified form of the aerator for a sewage system shown in FIG. 1;

FIG. 8 is a top plan view of FIG. 7;

FIG. 9 is a bottom plan view of FIG. 7;

FIG. 10 is an elevational view taken 90 degrees from FIG. 7;

FIG. 11 is an elevational view taken 90 degrees from FIG. 10;

FIG. 12 is an elevational view taken 90 degrees from FIG. 11;

FIG. 13 is an elevational view of a second modified form of the aerator for a sewage system shown in FIG. 1;

FIG. 14 is a top plan view thereof;

FIG. 15 is a bottom plan view thereof;

FIG. 16 is an elevational view taken 90 degrees from FIG. 13;

FIG. 17 is an elevational view taken 90 degrees from FIG. 16; and

FIG. 18 is an elevational view taken 90 degrees from FIG. 17.

This is a continuation of design application Ser. No. 276,078, filed July 28, 1972, now abandoned.

I claim:

The ornamental design for an aerator for a sewage system, substantially as shown and described.
